Primary Examiner — Robert M Spear*Assistant Examiner* — Kendra L Hamilton(74) Attorney, Agent, or Firm — Fitch, Even, Tabin & Flannery LLP(57) CLAIM

I claim the ornamental design for a pacifier, as shown and described.

DESCRIPTION

FIG. 1 is a perspective view of a pacifier showing my new design;

FIG. 2 is a top plan view of the pacifier of FIG. 1;
FIG. 3 is a right side elevational view of the pacifier of FIG. 1, the left side elevational view being a mirror image of FIG. 3;
FIG. 4 is a rear elevational view of the pacifier of FIG. 1; and,
FIG. 5 is a front elevational view of the pacifier of FIG. 1.
The broken lines illustrate environmental structure and form no part of the claimed design.1 Claim, 1 Drawing Sheet(56) References Cited*U.S. PATENT DOCUMENTS
